Harold A. Barnacle, Gatlinburg, Tenn.

Application August 26, 1953, Serial No. 26,586

Term of patent 14 years

(Cl. D48—20)

To all whom it may concern:

Be it known that I, Harold A. Barnacle, a citizen of the United States, residing at Gatlinburg, Tennessee, have invented a new, original, and ornamental Design for a Table Lamp, of which the following is a specification, reference being had to the accompanying drawing, forming part thereof.

Fig. 1 is a side view in elevation of a table lamp showing my new design.

Fig. 2 is an end view of the same.

Fig. 3 is a top view of the same.

Fig. 4 is a bottom view of the same.

The dominant features of my design are shown in solid lines.

I claim:

The ornamental design for a table lamp, substantially as shown and described.
